UNITED STATES PATENT OFFICE.

HARRY P. FAIRCHILD, OF NEW YORK, N. Y.

DESIGN FOR A HANDLE FOR BUTTON-HOOKS, &c.

SPECIFICATION forming part of Design No. 21,404, dated March 15, 1892.

Application filed February 18, 1892. Serial No. 422,038. Term of patent 3½ years.

To all whom it may concern:

Be it known that I, HARRY P. FAIRCHILD, a citizen of the United States, residing at New York, in the county of New York and State of New York, have invented a certain new Design for a Handle, of which the following is a specification.

My invention consists of a new design for a handle for button-hooks, nut-picks, cutlery, or any similar article requiring a handle.

The design is clearly shown by the accompanying drawing, to which reference is made for a complete illustration of the same.

While the handle is shown applied to a button-hook, it will of course be understood that

the design is applicable to the handle of any similar article, it being customary to make the handle with the design thereon separately and then attach it to the various articles as desired.

What I claim as my invention is—

The design for a handle, as herein shown and described.

In witness whereof I hereunto set my hand in the presence of two witnesses.

HARRY P. FAIRCHILD.

Witnesses:

L. FRED HURD,
HENRY BARR.
